[57] CLAIM

The ornamental design for a pole storage stand, as shown and described.

DESCRIPTION

FIG. 1 is a perspective view of a pole storage stand; FIG. 2 is a side view of stand FIG. 1; and,

FIG. 3 is a plan view of stand FIG. 1.

The mesh part of the bag is fragmentarily shown in FIG. 2 for clarity of illustration, in order to fully disclose the verticle pole and support bracket for the bag.
